RAILWAY BRAKING APPARATUS

Delbert F. Cebourn, Portsmouth, Ohio, assignor to
The Union Switch & Signal Company, Swiss-
vale, Pa., a corporation of Pennsylvania

Application January 14, 1933, Serial No. 651,697

5 Claims. (Cl. 303—20)

My invention relates to railway braking apparatus, and particularly to braking apparatus of the type comprising wheel-engaging braking bars located beside a track rail, and movable toward 5 and away from the rail into braking and non-braking positions. More particularly, my invention relates to apparatus of the type described in which the braking bars are arranged to be moved to their braking positions by a fluid pressure operated motor or motors, and to be restored to their non-braking positions by suitable biasing means such as gravity.

One object of my invention is the provision of means for preventing the valve which controls 15 the admission of fluid pressure to the motor or motors from opening under any conditions unless the valve for exhausting fluid pressure from the motor or motors is then closed.

I will describe one form of apparatus embodying my invention, and will then point out the 20 novel features thereof in claims.

The accompanying drawing is a view, partly diagrammatic and partly cross sectioned, illustrating one form of apparatus embodying my 25 invention.

Referring to the drawing, the reference character 1 designates one track rail of a stretch of railway track, which track rail, as here shown, is secured to a rail support 2 mounted on an 30 adjacent pair of the usual crossties 3, only one crosstie being visible in the drawing. Associated with the rail 1 is a car retarder comprising two braking bars A¹ and A² located on opposite sides of the rail. Each of these braking bars comprises, as usual, a brake beam 4 and a brake shoe 5.

The braking bars A¹ and A² are arranged to be moved toward and away from the rail 1 through the medium of a lever 6 which is pivotally mounted at one end on a pivot pin 8 carried by the rail support 2, and a lever 7 which is pivotally mounted intermediate its ends on the pivot pin 9. The lever 6 is inclined upwardly and extends away from the rail 1 and is provided 45 in its upper surface with a groove 6^a which receives the braking bar A¹. The one end 7^a of the lever 7 is likewise inclined upwardly and extends away from the rail 1 at the opposite side of the rail from the lever 6, and the other end 7^b of the lever 7 is inclined downwardly and extends away from the rail 1 below the lever 6. The end 7^a of the lever 7 is provided in its upper surface with a groove 7^a, similar to the groove 6^a in the lever 6, which groove receives the 55 braking bar A². The parts are so arranged and

so proportioned that if the outer or free ends of the levers 6 and 7 are moved apart, the braking bars will be moved toward the rails into their effective or braking positions. When the braking bars occupy their braking positions, the brake 5 shoes will engage the opposite side faces of a car wheel traversing rail 1, and will retard the speed of the car. The center of gravity of the lever 6 and braking bar A¹ is considerably to the right of the pivot pin 8 so that this lever will 10 normally tend to rotate in a clockwise direction about the pivot pin. Similarly, the center of gravity of the lever 7 and braking bar A² is to the left of the pin 8 so that this lever will normally tend to rotate in a counter-clockwise direction about the pivot pin 8. It will be apparent, therefore, that when no force is applied to the free ends of the levers 6 and 7 to move them 15 apart, the free ends of these levers will move toward each other, thereby moving the braking 20 bars to their ineffective or non-braking positions in which they are illustrated in the drawing.

The levers 6 and 7 are arranged to be moved apart by means of a fluid pressure motor M comprising a cylinder 9 containing a reciprocable 25 piston 10 which is attached to the inner end of a piston rod 11. The cylinder 9 is pivotally connected with the free end of the lever 6 by means of trunnions 12 formed on the side of the cylinder and extending through bifurcations 13 formed 30 on the lever 6, while the piston rod 11 is connected at its free end with the free end 7^b of the lever 7 by means of an adjustable eyebolt 14 and a pivot pin 15. Fluid pressure may be admitted to the cylinder 9 on the upper side of 35 the piston 10 through an opening 16 which is threaded to receive a pipe 17. When fluid pressure is admitted to the cylinder 9 through the pipe 17 and opening 16, the piston 10 will be forced downwardly and the cylinder 9 upwardly, 40 thereby separating the levers 6 and 7, and hence moving the braking bars toward their effective or braking positions. It will be obvious that when the braking bars are moved to their braking positions, they will exert a braking force which is 45 proportional to the pressure of the fluid supplied to the cylinder 9.

The supply of fluid pressure to the cylinder 9 is controlled by means of two fluid pressure operated poppet valves 18 and 19, which poppet valves, in 50 turn, are controlled by means of two pilot valves V¹ and V². These pilot valves are similar, and each comprises a valve stem 20 biased to an upper position by means of a spring 21 and provided with a winding 22 and an armature 23. When 55

valve V^1 is energized, valve stem 20 of this valve moves downwardly against the bias exerted by the associated spring 21 , and under these conditions a pipe 25 is connected with a pipe 27 which 5 is constantly supplied with fluid pressure, usually compressed air, from a suitable source not shown in the drawing. When valve V^1 is deenergized, however, as shown in the drawing, pipe 25 is then disconnected from pipe 27 and is connected with 10 atmosphere through a port 26 .

When valve V^2 is energized, as shown in the drawing, valve stem 20 of this valve moves downwardly and connects pipe 27 with a pipe 28 , but when valve V^2 is deenergized, pipe 27 is disconnected from pipe 28 and is connected with atmosphere through a port 29 .

The two fluid pressure operated poppet valves 18 and 19 are both located in the same valve body 30 , and associated with each poppet valve is a 20 spring 18^a or 19^a which constantly biases the valve to a closed position. Formed in the valve body 30 above the valve 18 , and in axial alignment therewith, is a cylinder 32 containing a reciprocable piston 33 which is operatively connected 25 with the valve 18 . The upper end of cylinder 32 is connected with the previously described pipe 25 , and it will be apparent, therefore, that when valve V^1 is deenergized so that pipe 25 is connected with atmosphere, spring 18^a will hold valve 18 30 closed and piston 33 in its upper position, but that, when valve V^1 is energized, so that pipe 25 is connected with pipe 27 , the fluid pressure which is then supplied to pipe 25 will force piston 33 to its lower position, thus opening valve 18 . When 35 valve 18 is opened, cylinder 9 of motor M is connected with pipe 27 through pipe 17 , a chamber 35 formed in valve body 30 , valve 18 , and a chamber 34 formed in valve body 30 ; but when this valve is closed, cylinder 9 is disconnected from 40 pipe 27 .

The valve body 30 is also formed with a second cylinder 36 containing a reciprocable piston 37 which is operatively connected with the valve 19 , and the upper side of which is subjected to 45 the pressure in the pipe 28 . When valve V^2 is energized, the fluid pressure which is then supplied to pipe 28 forces piston 37 to its lower position thereby opening valve 19 , and under these conditions, cylinder 9 of motor M becomes connected with atmosphere through pipe 17 , chamber 35 , valve 19 , a chamber 38 formed in valve body 30 and a pipe 39 . When valve V^2 is deenergized, however, spring 19^a moves valve 19 to its closed position and piston 37 to its upper position, thus, disconnecting cylinder 9 from atmosphere. 55

It follows from the foregoing that when valve V^1 is energized, fluid pressure will be supplied to cylinder 9 from pipe 27 , and that, when valve V^2 is energized, cylinder 9 will become connected with atmosphere.

The valves V are controlled in part by a plurality of pressure responsive devices, each designated by the reference character P with a distinguishing exponent. Referring to the pressure responsive device P^5 , for example, this device comprises a Bourdon tube 40 connected with the pipe 28 , and subjected to the pressure on the upper side of piston 37 . The Bourdon tube 40 controls a contact $41-41^a$ which is open at all times except when the pressure in pipe 28 is below a predetermined pressure, for example, 5 pounds per square inch, which pressure is somewhat below the pressure at which valve 19 closes. The pressure responsive devices P^{20-30} , P^{45-55} and P^{70-80} , 65 70 are similar to the pressure responsive device P_5 , 75

except that the Bourdon tube 40 of each of these devices is connected with the pipe 17 which communicates with the cylinder 9 of motor M. The devices P^{20-30} , P^{45-55} and P^{70-80} are arranged to operate in succession as the pressure in cylinder 9 increases. For example, for all pressures below 20 pounds per square inch, contact $41-41^a$ of each of these devices is closed. If the pressure exceeds 20 pounds per square inch, contact $41-41^a$ of device P^{20-30} opens, and, if the pressure exceeds 30 pounds per square inch, contact $41-41^b$ of pressure responsive device P^{20-30} closes. In similar manner, the pressure responsive devices P^{45-55} and P^{70-80} are adjusted to open their contacts $41-41^a$ at 45 and 70 pounds per square inch, respectively, and to close their contacts $41-41^b$ at 55 and 80 pounds per square inch. Of course, these specific pressures are not essential, but are only mentioned for purposes of illustration.

The valves V are also controlled by means of a manually operable lever L which, as here shown, is capable of assuming five positions, indicated by dotted lines in the drawing, and designated by the reference characters p^1 to p^5 , inclusive. The lever L controls a plurality of contacts, each designated by the reference character 42 with a distinguishing exponent corresponding to the position of the lever in which the corresponding contact is closed. For example, contact 42^1 is closed 30 in the p^1 position of the lever, contact 42^2 in the p^2 position of the lever, etc.

Lever L will usually be located at a point remote from the braking apparatus, as in the control cabin of a classification yard car retarder 35 system, and will be connected with the braking apparatus by means of line wires extending from the control cabin to the braking apparatus.

As shown in the drawing, lever L occupies its p^1 or "off" position, which is the position which this lever normally occupies when no cars are to be retarded, and all of the contacts of lever L , with the exception of contact 42^1 , are therefore open. Valve V^1 is deenergized, but valve V^2 is energized over a circuit which passes from a suitable source 45 of current here shown as a battery B, through wire 43 , contact 42^1 of lever L , line wire 44 , wire 45 , winding 22 of valve V^2 , wire 46 , and line wire 47 back to battery B. Since valve V^1 is deenergized, valve 18 is closed and the supply of fluid pressure to motor M is therefore cut off, and since valve V^2 is energized, valve 19 is open so that cylinder 9 is connected with atmosphere. The braking bars are therefore held in their ineffective or non-braking positions by gravity. 50 Contact $41-41^a$ of each of the pressure responsive devices P^{20-30} , P^{45-55} and P^{70-80} is closed, while contact $41-41^b$ of pressure responsive device P^5 and contact $41-41^b$ of each of the other pressure responsive devices is open.

In explaining the operation of the apparatus as a whole, I will first assume that the operator wishes to make a comparatively light brake application. To do this, he moves lever L from its p^1 to its p^2 position, thereby opening contact 42^1 65 of lever L and closing contact 42^2 . The opening of contact 42^1 interrupts the circuit which was previously closed for valve V^2 at this contact, and valve V^2 therefore now becomes deenergized and disconnects pipe 28 from pipe 27 and connects pipe 28 with atmosphere. When pipe 28 becomes connected with atmosphere, the pressure in this pipe and in the upper end of cylinder 36 decreases rapidly, and as soon as the pressure has decreased to a predetermined value, for example, 70 75

15 pounds per square inch, spring 19^a closes valve 19 thus disconnecting cylinder 9 from atmosphere. When the pressure in pipe 28 has decreased to 5 pounds per square inch, contact 41—41^a of pressure responsive device P⁵ becomes closed, and a circuit is then completed for valve V², which circuit may be traced from battery B through wire 48, contact 42² of lever L, line wire 49, contact 41—41^a of pressure responsive device P²⁰⁻³⁰, wire 50, contact 41—41^a of pressure responsive device P⁵, wire 51, winding 22 of valve V¹, and line wire 47 back to battery B. Valve V² therefore becomes energized and connects pipe 27 with pipe 25, thus causing piston 33 to move 10 downwardly and open valve 18. As was previously pointed out, when valve 18 is opened, pipe 27 becomes connected with pipe 17, and fluid at full line pressure is therefore now supplied to cylinder 9 to move the braking bars to their braking 15 positions. As soon as the fluid in the upper end of cylinder 9 reaches 20 pounds per square inch, contact 41—41^a of pressure responsive device P²⁰⁻³⁰ opens and interrupts the circuit just traced for valve V¹. Valve V¹ then becomes deenergized, thus causing valve 18 to become closed and hence cutting off the supply of fluid pressure to the upper end of cylinder 9. Valve V¹ will now remain deenergized until the pressure in cylinder 9 again decreases below 20 pounds per 20 square inch, at which time contact 41—41^a of pressure responsive device P²⁰⁻³⁰ will reclose and reestablish the circuit for valve V¹. Valve 18 will then again become opened and readmit fluid to cylinder 9. If the fluid in cylinder 9 now increases to a pressure of 30 pounds per square inch for any reason, contact 41—41^b of pressure responsive device P²⁰⁻³⁰ will become closed and will complete another circuit for valve V², this circuit passing from battery B through wire 48, 25 contact 42² of lever L, line wire 49, contact 41—41^b of pressure responsive device P²⁰⁻³⁰, an asymmetric unit R in its low resistance direction, wire 45, winding 22 of valve V¹, wire 46, and line wire 47 back to battery B. Valve V² will therefore now become energized and will cause valve 19 to open, thus venting fluid from cylinder 9. Valve 19 will continue to vent fluid from cylinder 9 until the pressure in cylinder 9 has decreased to 30 pounds per square inch at which time contact 41—41^b of pressure responsive device P²⁰⁻³⁰ will open and will deenergize valve V². When valve V² becomes deenergized, valve 19 will reclose and prevent further escape of fluid from cylinder 9. Furthermore, shortly after valve 19 has closed, 30 contact 41—41^a of pressure responsive device P⁵, which contact became opened when valve V² became energized, will again become closed, so that if the pressure in cylinder 9 again decreases to the value at which contact 41—41^a of pressure responsive device P²⁰⁻³⁰ closes, the circuit for valve V¹ will be reestablished. It will be seen, therefore, that when lever L occupies its p² position, the braking bars will be held in their braking positions by a pressure of between 20 and 30 35 pounds per square inch.

If the operator desires to make a more powerful brake application, he moves lever L to its p³ position in which contact 42³ is closed. Under these conditions, valve V² will be deenergized, and valve V¹ will become energized over a circuit which passes from battery B through wires 43 and 52, contact 42³ of lever L, line wire 53, contact 41—41^a of pressure responsive device P⁴⁵⁻⁵⁵, wires 54 and 50, contact 41—41^a of pressure responsive device P⁵, wire 51, winding 22 of valve V¹, and line wire 47 back to battery B. Fluid pressure will therefore now be admitted to the upper end of cylinder 9 until the pressure of the fluid in the cylinder increases to 45 pounds per square inch, at which pressure contact 41—41^a of pressure responsive device P⁴⁵⁻⁵⁵ will open and will deenergize valve V¹. If the pressure in the upper end of cylinder 9 now increases to 55 pounds per square inch, contact 41—41^b of pressure responsive device P⁴⁵⁻⁵⁵ will become closed and will complete another circuit for valve V², this latter circuit passing from battery B through wires 48 and 52, contact 42³ of lever L, line wire 53, contact 41—41^b of pressure responsive device P⁴⁵⁻⁵⁵, asymmetric unit R in its low resistance direction, wire 45, winding 22 of valve V¹, wire 46, and line wire 47 back to battery B. The resultant energization of valve V² will cause valve 19 to open, thus exhausting fluid from cylinder 9 in a manner which will be readily understood from the foregoing description. Valve V² will now remain energized until the pressure of the fluid in cylinder 9 has decreased below 55 pounds per square inch at which time contact 41—41^b of pressure responsive device P⁴⁵⁻⁵⁵ will open and will interrupt the circuit for valve V². Valve 19 will then reclose and after this valve has closed, contact 41—41^a of pressure responsive device P⁵ will close. It will be apparent, therefore, that when lever L occupies its p³ position, the braking bars will be held in their braking positions by a pressure of between 45 and 55 pounds per square inch.

If the operator moves lever L to its p⁴ position, valve V¹ will become energized over a circuit which passes from battery B through wires 48, 52, and 56, contact 42⁴ of lever L, line wire 57, contact 41—41^a of pressure responsive device P⁷⁰⁻⁸⁰, wires 58, 54, and 50, contact 41—41^a of pressure responsive device P⁵, wire 51, winding 22 of valve V¹, 40 and wire 47 back to battery B. Under these conditions, fluid will be supplied to the upper end of cylinder 9 until the pressure in the cylinder reaches 70 pounds per square inch, which is the pressure at which contact 41—41^a of pressure responsive device P⁷⁰⁻⁸⁰ opens. If the pressure in cylinder 9 now increases to 80 pounds per square inch, contact 41—41^b of pressure responsive device P⁷⁰⁻⁸⁰ will become closed and will complete still another circuit for valve V². This latter circuit for valve V² may be traced from battery B through wires 48, 52, and 56, contact 42⁴ of lever L, line wire 57, contact 41—41^b of pressure responsive device P⁷⁰⁻⁸⁰, asymmetric unit R in its low resistance direction, wire 45, winding 22 of valve V¹, wire 46, and line wire 47 back to battery B. Valve V² will therefore become energized and cause valve 19 to open until the pressure in the upper end of cylinder 9 again decreases to 80 pounds per square inch. When valve V² becomes energized, contact 41—41^a of pressure responsive device P⁵, of course, becomes opened and remains opened until valve 19 has closed following the deenergization of valve V². It will be seen, therefore, that when lever L is moved to its p⁴ position, cylinder 9 is supplied with fluid at a pressure of between 70 and 80 pounds per square inch, and the braking bars therefore exert a corresponding braking force.

If the operator desires to cause the braking bars 70 to exert their maximum braking force, he moves lever L to its p⁵ position. Under these conditions, valve V¹ becomes energized and subsequently remains energized over a circuit which passes from a battery C, through line wire 47, winding 22 of valve V¹

valve V^1 , wire 51, contact 41—41^a of pressure responsive device P^5 , wires 59, 54, and 58, an asymmetric unit S in its low resistance direction, line wire 57, contact 42^b of lever L, and wire 59 back to battery C. The energization of valve V^1 , of course, causes valve 18 to open, and when valve 18 becomes opened, fluid at full line pressure is supplied to the upper end of cylinder 9. It will be apparent, therefore, that under these conditions, the braking bars are held in their braking positions by fluid at full line pressure.

It should be observed that if the operator moves lever L from a position corresponding to a higher braking force to a position corresponding to a lower braking force, the apparatus will immediately and automatically reduce the braking pressure to a value corresponding to the new position of the lever in a manner which will be apparent from the drawing without tracing the sequence of operation in detail.

When lever L occupies any position but its p^1 position, so that the braking bars occupy their braking positions, and the operator wishes to restore the braking bars to their non-braking positions in which they are illustrated in the drawing, he restores lever L to its p^1 or "off" position. When he does this, all circuits previously traced for valve V^1 are interrupted, and the circuit previously traced for valve V^2 including contact 41^b of lever L becomes closed. Valve V^1 therefore becomes deenergized and valve V^2 becomes energized, thus causing valve 18 to close and valve 19 to open. As a result, the supply of fluid pressure to the upper end of cylinder 9 is cut off, and the fluid which was previously supplied to the cylinder is vented to atmosphere. The braking bars will therefore move, under the influence of gravity, to their ineffective or non-braking positions. When the fluid has been completely vented from cylinder 9, the contacts 41—41^a of the pressure responsive devices P^{20-30} , P^{45-55} and P^{70-80} will all be closed and the contacts 41—41^b of these pressure responsive devices will all be open. Furthermore, since valve V^2 is now energized, contact 41—41^a of pressure responsive device P^5 will be opened. As a result, when the braking bars reach their non-braking position, all parts will be restored to the positions in which they are shown in the drawing.

It should be particularly pointed out that with the apparatus constructed as shown in the drawing, it is impossible under any conditions for valve V^1 to become energized unless contact 41—41^a of pressure responsive device P^5 is closed, and contact 41—41^b will not become closed unless the pressure in pipe 28 is below the pressure at which valve 19 becomes closed. It follows that under no conditions will valve 18 become opened while valve 19 is open, and as a result, there can be no loss of fluid due to fluid flowing from pipe 27 through chamber 34, valve 18, chamber 35, valve 19, chamber 36, and pipe 39 to atmosphere.

Although I have herein shown and described only one form of railway braking apparatus embodying my invention, it is understood that various changes and modifications may be made therein within the scope of the appended claims without departing from the spirit and scope of my invention.

Having thus described my invention, what I claim is:

1. In combination, a fluid pressure operated device, a first fluid pressure operated valve for controlling the admission of fluid pressure to said device, a second fluid pressure operated valve for

controlling the exhaust of fluid pressure from said device, an electrical contact which becomes opened whenever said second valve becomes opened and which when once opened remains opened until after said second valve again becomes closed, means for controlling the supply of fluid pressure to said second valve, and means including said contact for controlling the supply of fluid pressure to said first valve.

2. In combination, a fluid pressure operated device, two fluid pressure operated valves for controlling the supply of fluid pressure to, and exhaust of fluid pressure from, said device, means for supplying fluid pressure to one of said valves, an electrical contact responsive to the pressure of the fluid supplied to said one valve and arranged to open at a predetermined pressure, and means controlled by said contact for controlling the supply of fluid pressure to the other valve.

3. In combination, a fluid pressure operated device, two fluid pressure operated valves, one for controlling the supply of fluid pressure to, and the other for controlling the exhaust of fluid pressure from, said device, means for controlling the supply of fluid pressure to said other valve, and electrically operated means responsive to the pressure of the fluid supplied to said other valve for controlling the supply of fluid pressure to said one valve.

4. Railway braking apparatus comprising two braking bars movable toward and away from a track rail into braking and non-braking positions and biased to a non-braking position, a fluid pressure motor for moving said braking bars to their braking positions, a first fluid pressure operated valve for controlling the admission of fluid pressure to said motor, a second fluid pressure operated valve for controlling the exhaust of fluid pressure from said motor, a first electropneumatic pilot valve for controlling the supply of fluid pressure to said first fluid pressure operated valve, a second electropneumatic pilot valve for controlling the supply of fluid pressure to said second fluid pressure operated valve, a contact, means responsive to the pressure of the fluid supplied to said second fluid pressure operated valve for operating said contact, said means being so adjusted that said contact will become opened whenever said second valve becomes opened and will remain open until after said second valve has subsequently become closed, a manually operable lever, a circuit for said second electropneumatic valve controlled by said lever, and a circuit for said first electropneumatic valve controlled by said lever and including said contact.

5. Railway braking apparatus comprising two braking bars movable toward and away from the track rails into braking and non-braking positions and biased to a braking position, a fluid pressure motor for moving said braking bars to their braking positions, a first fluid pressure operated valve for controlling the exhaust of fluid pressure from said motor, manually controlled means for at 65 times supplying fluid pressure to said valve to open said valve, a contact responsive to the pressure of the fluid supplied to said valve and arranged to become opened whenever said valve becomes opened and to subsequently remain open until after said valve again becomes closed, and means controlled in part by said contact for controlling the admission of fluid pressure to said motor.
